UNITED STATES PATENT OFFICE.

GEORGE SINCLAIR, OF ST. PAUL, MINNESOTA, ASSIGNOR OF ONE-THIRD TO WILLIAM J. BABCOCK AND ONE-THIRD TO EMIL R. BROKOFF, BOTH OF ST. PAUL, MINNESOTA.

MILKING APPARATUS.

1,139,589.

Specification of Letters Patent. Patented May 18, 1915.

Application filed October 26, 1914. Serial No. 868,677.

To all whom it may concern:

Be it known that I, GEORGE SINCLAIR, a citizen of the United States, residing at St. Paul, in the county of Ramsey and State of Minnesota, have invented a new and useful Improvement in Milking Apparatus, of which the following is a specification.

The object of this invention is the production of improved milking apparatus, which 10 can be employed to efficiently milk a single or plurality of cows simultaneously.

This invention provides simple and inexpensive construction, which can be operated by a minimum amount of power, and 15 which is sanitary, the parts being easily cleaned and providing a minimum number of projections and crevices, in which disease breeding germs might collect.

To these ends this invention comprises the 20 features of construction, and combination of parts hereinafter described and set forth in the claims.

In the accompanying drawing forming part of this specification, Figure 1 is a detail partly in section of my invention, illustrating the pumping apparatus which is employed; Fig. 2 is a side elevation partly in section of the milking apparatus, which is adapted to be connected with the pumping mechanism, and Fig. 3 is a plan of the apparatus illustrated in Fig. 2.

In the drawing A indicates a cylinder having a wall 2 across its central portion midway between its ends for the purpose 25 of forming the cylinder into two separate cylindrical chambers in each of which a piston such as 3 is reciprocable. The cylinder is adapted to be mounted by bosses 4 on its side upon a stanchion or other suitable support in close proximity to the cows 30 which are to be milked. As many of these cylinders may be provided with their accompanying co-operating parts as are desirable, a cylinder preferably being employed 40 for every couple of cows to be milked. Connected with the piston, by piston rods such as 5 is a reciprocable operating shaft 6, which is provided with socket pieces 7 into which the ends of the piston rods can be 45 separably hooked to form an operable connection. The position of the socket members permits the fastening of the piston rods, so that a pair of the pistons will reciprocate in the cylinder, one piston being positioned at the inner end of a stroke while

the other piston is at the outer end of a stroke. In this manner the two pistons which are reciprocated simultaneously produce a suction and compression stroke at the same time. The cylinder is formed with 60 inlet ports 8 for the admission of air into the cylinder chambers when the pistons reach their outermost positions in the cylinder. Near the inner end of each piston chamber is another port such as 9, in which 65 a nipple 10 is secured, so that a flexible tube 11 can be attached thereto. The passages in the flexible tubes 11 communicate with a milk receiving chamber B, which is in the form of a pail 12 or other suitable 70 portable container having a removable cover 13, which is adapted to be placed in closed position over the top thereof. This cover has secured thereto what I have chosen to term a pulsator C, which consists of a pair 75 of oppositely disposed coupling elements 14 and 15, which are mounted apart upon the cover and secured thereto by threading a pair of pipes constituting milk pocket ducts 16 and 17, said pipes passing through the 80 cover and being curved downwardly therefrom and inwardly with their lower ends facing and terminating closely adjacent each other. Nipple unions 18 and 19 are threaded into the upper ends of the coupling elements 14 and 15 to which the flexible tubes 11 are attached, thus producing 85 a suction connection between each chamber of the pump and one of said milk receiving pockets. Located immediately below each 90 nipple 18 or 19, which is mounted upon one of the coupling elements 14 or 15 are a pair of laterally extending ports 20 and 21 to which a pair of flexible milking tubes 22 and 23 are connected, the outer extremities of 95 these milking tubes being provided with flexible teat cups 24 of usual form, which are mounted thereon by means of the holders 25 in the usual manner.

In order that suction may be produced 100 first in one pair of teat cups and then in the other, which are mounted upon a pair of the milking tubes 22 and 23, the pulsator is provided with a flap valve 26, which is hung freely by a link 27 from the cover of the receptacle, said valve being positioned freely in the space between the adjacent ends of the downwardly extending incurved milk pocket ducts 16 and 17, so that when air is exhausted from one of said pipes 16 or 17, 110

the valve closes that pipe and allows the opposite one to open freely into the receptacle B allowing any milk which has collected in the open pipe to flow into the receptacle. 5 The valve is reciprocated due to the reciprocation of the pump, thus producing a pulsating action in each pair of milking tubes, and causing the milk which is drawn from the cow through the milking tubes to 10 first collect in one of the pocket ducts which is closed by the valve 26 and during the next pulsation of the valve to flow freely from said pocket duct into the receptacle while milk is being collected in the opposite 15 pocket duct. By this construction, it will be observed that a simple and efficient double acting apparatus is produced, which is capable of quickly milking a plurality of cows simultaneously. As soon as it is desired to discontinue the operation of the apparatus the connecting rods 5 can be disconnected from the prime moving reciprocating element 6.

In accordance with the patent statutes, I 25 have described the principles of operation of my invention, together with the apparatus which I now consider to represent the best embodiment thereof, but I desire to have it understood that the construction 30 shown is only illustrative and that the invention can be carried out by other means and applied to uses other than those above set forth within the scope of the following claims.

35 Having described my invention, what I claim as new and desire to protect by Letters Patent is:—

1. A milking apparatus, comprising, in combination, a milking receptacle, a pair of 40 coupling elements mounted upon said receptacle having milk pocket ducts extending downwardly from said coupling elements into said receptacle and terminating with their lower ends adjacent and spaced 45 apart, a flap valve hung between said adjacent ends of said milk pocket ducts and adapted through the alternate drawing of air upwardly through said ducts to close one of said ducts and assist in forming a 50 trap therein for milk and open the other and permit milk therein emptying into said receptacle, milking and suction tubes con-

nected with said coupling elements and a pump connected with said suction tubes adapted to reciprocate said valve and to 55 produce a suction action first in one and then another of said milking tubes, for the purposes specified.

2. Milking apparatus, comprising, in combination, a milk receptacle, a pair of 60 coupling elements mounted upon a wall of said receptacle and having milk receiving ports, a pair of milk pocket ducts in communication with said ports and extending down into said receptacle, said milk pocket 65 ducts being placed with their lower ends opening into said receptacle and positioned substantially adjacent and spaced slightly apart, a flap valve hung freely in the interval between the lower ends of said milk 70 receiving pockets and adapted to move freely to alternately open and close each of the openings in the lower ends of said milk receiving pockets, a double acting pump having a pair of cylinder chambers with 75 pistons reciprocable therein, flexible connections leading from said chambers and connected with said coupling elements and a reciprocable prime mover with which said piston elements are adapted to be separably 80 coupled, said piston elements being adapted to alternately exhaust air upwardly through first one of said milk receiving pockets and then the other.

3. In apparatus of the class set forth, a 85 pulsator comprising in combination with a receptacle, a pair of coupling elements mounted upon a wall of said receptacle having milk receiving and air suction ports and downwardly and inwardly extending milk 90 pocket ducts having openings at their lower ends facing together and spaced apart, and a flap valve movably supported to reciprocate freely in the interval between said openings and adapted to alternately close and 95 open each of said openings.

In testimony whereof, I have signed my name to this specification, in the presence of two subscribing witnesses.

GEORGE SINCLAIR.
